(57) CLAIM

The ornamental design for a shoe, as shown and described.

DESCRIPTION

FIG. 1 is a left side view of a shoe showing my new design;

FIG. 2 is a front elevation view thereof;

FIG. 3 is a top plan view thereof; and,

FIG. 4 is a rear elevation view thereof.

Broken lines depict unclaimed portions of the sport shoe. The bottom and right sides of the shoe do not show any claimed subject matter and so are not depicted in the figures.
